UNITED STATES PATENT OFFICE.

PETER E. WHITSON, OF CHICAGO, ILLINOIS, ASSIGNOR TO MUELLER BROTHERS ART AND MANUFACTURING COMPANY, OF CHICAGO, ILLINOIS, A CORPORATION OF ILLINOIS.

DESIGN FOR A FRAME.

47,127

Specification for Design.

Patented Mar. 16, 1915.

Application filed May 8, 1914. Serial No. 837,337. Term of patent 7 years.

To all whom it may concern:

Be it known that I, PETER E. WHITSON, a citizen of the United States, residing at Chicago, in the county of Cook and State of Illinois, have invented a new, original, and ornamental Design for Frames, of which the following is a specification, reference being had to the accompanying drawing, forming part thereof.

In said drawing, Figure 1, is a face view of a frame showing my new design; Fig. 2,

is a cross-section taken on line 2—2— of Fig. 1, and Fig. 3, is a cross-section taken on line 3—3— of Fig. 1.

I claim—

The ornamental design for a frame, as shown.

PETER E. WHITSON.
